UNITED STATES PATENT OFFICE

ERICK O. FELLROTH, OF MINNEAPOLIS, MINNESOTA, ASSIGNOR TO MARTIN BROTHERS COMPANY, OF MINNEAPOLIS, MINNESOTA, A CORPORATION OF MINNESOTA

OVERALLS

Application filed June 21, 1926. Serial No. 117,385.

My invention relates to overalls and has for an object thereof to provide an improved garment of such construction formed with a drop seat, provided with straps or belt members for holding the same in position, said straps upon being tightened being adapted to draw the drop seat taut so as to cause the same snugly to fit the body of a wearer.

Another object of the invention resides in forming said drop seat with a waist band along the upper portion of the same, having loops attached to the ends thereof, and to pass said straps through said loops, said straps being attached, each at one end thereof, to the body of the garment forwardly of said loops and above the waistline, said straps having fastening members at their free ends for securing the same together and in place around the waist of the wearer.

20 A still further object of the invention resides in forming extensions on the body portion of the overall adapted to underlie the marginal portions of said drop seat at the sides thereof and to form pockets on said 25 extensions having the openings thereof approximately aligned or registering with the free side edges of said drop seat, so that upon the drawing of the strap members together to hold the drop seat in place, the openings 30 to said pockets become closed and said pockets caused to lie snugly against the body of the wearer.

With the foregoing and other objects in view, which will appear in the following description, the invention resides in the novel combination and arrangement of parts and in the details of construction hereinafter described and claimed.

35 In the drawings illustrating my invention 40 in one form:

Fig. 1 is a fragmentary front elevational view of an overall showing an embodiment of my invention.

Fig. 2 is a rear view of the garment illustrated in Fig. 1.

Fig. 3 is a side elevational view of the garment shown in Fig. 1.

Fig. 4 is an enlarged detailed view of the seat portion of the garment illustrating the 50 drop seat in lowered position.

For the purpose of illustrating the invention I have shown a garment indicated in its entirety at A, which generally simulates in appearance an ordinary pair of overalls. This garment comprises a body portion 10 55 adapted to cover the hips and waist of the wearer, which body portion has attached to it legs 11 and 12. This overall is constructed of a front 13 and a back 14 forming the body portion 10 and the legs 11 and 12, 60 which front 13 extends upwardly to provide a bib 15.

At the upper portion of the back 14, at either side thereof, V-shaped portions of material are cut away to form a drop seat 16. 65 This drop seat, so formed, has upwardly converging free edges 18 and 19, also an upper free edge, which I bind with a waist band 20. Said drop seat 16 in raised or closed position assumes the appearance disclosed in 70 Figs. 2 and 3.

For closing the sides of the garment adjacent the free edges 18 and 19 of the drop seat 16, I employ extensions 21 and 22 of the body portion 10, which underlie said edges 75 18 and 19 of said drop seat, as clearly shown in Fig. 2. The garment is supported upon the body of a wearer by means of two suspenders or shoulder straps 23 and 24, each of which is attached at one end to the upper portion of the apron 15, and at the other end to one of the body extensions 21, 22. These suspenders are provided with buckles 25 so that the same way may be adjusted to properly hold the garment supported on the body of 80 85 the user in the ordinary and customary manner.

Upon the body extensions 21 and 22 are pocket pieces 26 and 27 sewed thereto along lines 28. These pocket pieces provide pockets 90 opening along the edges 29 of said pieces. It will be noted that said pocket openings are positioned immediately under the edges 18 and 19 of the drop seat 16, so that when said drop seat is closed it will cover said pockets, 95 said edges coinciding with the openings to said pockets and holding the pockets closed against the body of the wearer.

For the purpose of holding the drop seat 16 in closed position, I employ two belt mem- 100

bers or straps 30 and 31, which pass through loops 32 secured to the ends of the waist band 20 on said drop seat. These straps are, as at 5, attached to the edges 33 and 34 of the bib 15 somewhat above the waistline of the garment and above the normal elevation of the waist band 20. Said straps are adjustable as to length at their other ends and are fitted with complementary fastening members 36 and 10 37, which are adapted to be hooked together at the front of the garment to secure the drop seat closed, as shown in Figs. 1 and 2. When the drop seat is lowered, as illustrated in Fig. 4, straps 30 and 31 extend loosely through the 15 loops 32 permitting the said drop seat to be fully opened to give the user full comfort. Upon closing the drop seat by drawing said straps 30 and 31 through the loops 32, said drop seat is caused to be raised and the 20 edges 18 and 19 thereof drawn taut so that the said drop seat fits snugly upon the body of the user. Upon hooking the fastening members 36 and 37 together the garment is held in place as illustrated in Figs. 1, 2 and 3. 25 When the garment is so arranged it will be noted that the lower reaches 38 of the straps 30 and 31 extend around the waistline of the user while the upper reaches 39 thereof incline forwardly and upwardly from the 30 loops 32 secured to the waist band 20. This has the effect of exerting an upward forward pull upon the free corners of the drop seat and causes the edges 18 and 19 thereof and the waist band 20 to be drawn taut, whereby 35 the garment is snugly fitted to the body of the wearer. In this manner the side marginal portions of the drop seat are caused to press against the pockets 26 and 27 and hold the same flat against the wearer's body, the edges 40 18 and 19 of said drop seat holding the openings to said pockets closed, thereby preventing accidental displacement of the contents of the pockets.

The advantages of my invention reside particularly in the fact that the garment, even though over-sized, is caused to fit snugly and neatly about the body of the wearer so that an extremely comfortable and neat appearing overall is produced. The drop seat 45 is not only permitted to fit snugly upon the body extensions and the person of the wearer, but it is actually drawn up, upon sliding the straps or belt members in the act of raising said drop seat, so that when tension is put in 50 the belt, the said drop seat will at all times remain in perfect position in conformity with the contour of the figure of the user. By placing the hip pockets on the body extensions beneath the marginal side portions of the 55 drop seat, said pockets are caused to be held closed and the contents thereof are prevented from accidental displacement during the movement of the wearer in his usual activities.

60 65 Changes in the specific form of my invention,

tion, as herein disclosed, may be made within the scope of what is claimed without departing from the spirit of my invention.

Having described my invention, what I claim as new and desire to protect by Letters Patent is:

1. A garment of the class described, comprising a body portion having a drop seat having free edges along its sides and a waist band at the top thereof, loops secured to the ends of said waist band, a pair of straps passing through said loops, said straps being attached to said body portion forwardly of said drop seat at points above the waist line, and fastening means at the other ends of said straps for securing the same together at the front of the garment, said straps serving to draw the drop seat upwardly to close the same upon being tightened so as to cause said free edges of said drop seat to become taut and to cause said drop seat to fit snugly upon the body of the wearer. 75 80 85

2. A garment of the class described, comprising a body portion having a drop seat with free edges along the sides thereof, extensions formed on said body portion to underlie the free edges of said drop seat, pockets formed on said extensions adapted to be covered by said drop seat, and means for drawing said drop seat upwardly and upon said 90 pockets, said means having a point of attachment to said body portion above the waistline so as to cause said free edges to become taut and hold said pockets closed. 95

3. A garment of the class described, comprising a body portion formed with a drop seat having free edges along the sides thereof, extensions formed on said body portion underlying the free edges of said drop seat, pockets formed on said extensions adapted to be covered by said drop seat, said pockets having openings in approximate alignment with said free edges, and means for drawing said drop seat into place upon the body portion, said means having a point of attachment to said body portion above the drop seat so as to cause said free edges to become taut and close the openings to said pockets. 100 105 110

4. A garment of the class described, comprising a body portion formed with a drop seat having free edges along the sides thereof, extensions formed on said body portion underlying the free edges of said drop seat, pockets formed on said extensions adapted to be covered by said drop seat, said pockets having openings in alignment with said free edges, loops secured to said drop seat, a pair of straps passing through said loops, said straps being attached to said body portion forwardly of said drop seat at points above the waist line, and co-operating fastening means at the other ends of said straps for securing the same together at the front of the garment to draw the drop seat upwardly upon being tightened so as to cause said free 115 120 125 130

edges of said drop seat to become taut and close the openings to said pockets.

5. A garment of the class described comprising a body portion formed with a drop seat having free edges along the sides thereof, extensions formed on said body portion underlying the free edges of said drop seat, pockets formed on said extensions adapted to be covered by said drop seat, said pockets having openings in approximate alignment with said free edges, straps secured to said body portion above the waistline of the garment, said straps being slidable relative to said drop seat for drawing the same taut across the openings of said pockets, and means for holding said straps in drawn position.

6. A garment of the character described, including a body portion having a drop seat portion, the side edges of said seat portion 20 being free and converging in the direction of the upper edge of the seat portion, said body portion being formed with extensions underlying said drop seat at either side thereof, pockets formed in said extensions having converging openings disposed substantially beneath the converging edges of said seat portion, and suspender straps for the garment, the forward ends of said straps being connected to the front portion of the garment 25 and the rear ends thereof connected to said extensions, the latter connections being made to bring the rear portions of the straps in substantial alignment with the pocket openings, and means for holding the drop seat closed 30 against said pockets.

7. A garment of the class described comprising a body portion having a drop seat with free edges along its sides, loops secured to said drop seat at the upper portion thereof, a pair of straps passing through said loops, said straps being attached to said body portion forwardly of said drop seat at points above said loops to hold said free edges from gapping, and fastening means at the other 45 ends of said straps for securing the same together at the front of the garment.

8. A garment of the class described comprising a body portion having a drop seat with free edges along its sides, fastening members secured to said body portion, members for slidably connecting said fastening members to said drop seat, said fastening members being attached to said body portion at points above said last named members for holding the free edges of said drop seat from gapping.

9. A garment of the class described comprising a body portion having a drop seat with free edges along its sides, straps secured 50 to said body portion, members attached to said drop seat for slidably connecting said straps therewith, said straps being attached to said body portion at points above said members for drawing said drop seat in place 55 and holding the free edges thereof from gap-

ping, and means for holding said straps in drawn position.

10. A garment of the class described comprising a body portion and a drop seat with free edges along its sides, straps connected to said body portion and drop seat, said straps for said garment having portions oblique relative to the wearer's waistline connected to the drop seat and body portion for simultaneously drawing said drop seat upwardly 75 and forwardly to hold the free edges of the drop seat from gapping, means for holding said straps in drawn position, said connections of said straps to said body portion and drop seat serving to retain said drop seat in 80 closed position.

In testimony whereof I have affixed my signature.
